UNITED STATES PATENT OFFICE.

MITA MICHAJLOV, OF NEW YORK, N. Y.

ARTIFICIAL LIMB.

1,215,835.

Specification of Letters Patent. Patented Feb. 13, 1917.

Application filed July 19, 1916. Serial No. 110,250.

To all whom it may concern:

Be it known that I, MITA MICHAJLOV, a citizen of the United States, and resident of New York, in the county and State of New York, have invented certain new and useful Improvements in Artificial Limbs, of which the following is a full, clear, and exact specification.

This invention relates to artificial limbs, and has for one object to provide an improved foot structure which will operate more naturally than previous constructions. Another object is to provide improved cushioning means in the upper part of the limb, 15 to prevent the chafing of the stump.

Special objects are to provide an improved universal ball and socket joint between the foot and ankle portions of the limb, to improve the action of the toe portion of the foot, and to provide improved means for limiting the upward movement of the front portion of the foot with respect to the ankle section, said means being adjustable to suit different requirements. 25 Other objects will appear as the description proceeds.

The invention will be first hereinafter described in connection with the accompanying drawings which constitute part of this specification and then more specifically defined in the claims at the end of the description.

In the accompanying drawings, wherein similar reference characters are used to designate corresponding parts throughout the several views:

Figure 1 is a broken side elevation of an artificial limb constructed substantially in accordance with this invention.

40 Fig. 2 is a cross section on the line II—II of Fig. 1.

Fig. 3 is a detailed plan view of the I-shaped plate to which is attached the adjustable means for limiting the swinging of 45 the foot upon the ankle section.

Fig. 4 is a cross section on the line IV—IV of Fig. 1.

Fig. 5 is a plan view of the foot section alone.

50 Fig. 6 is a vertical section of the upper portion of the artificial limb, taken on the line VI—VI of Fig. 1.

Figs. 7 and 8 are detailed views of the ball member of the ball and socket joint between 55 the foot and ankle sections.

Fig. 9 is a detailed plan view of the

tongued washer plate which is fastened to the upper face of the foot section and constitutes a part of the adjusting means for limiting the swing of said foot section, and 60

Fig. 10 is a broken detailed view of the screw-threaded portion of said adjusting means.

The artificial limb comprises a top section 1, an ankle section 2 and a foot section 3. 65 The sections 1 and 2 are telescoped the former into the latter, said section 1 having a reduced portion 4 fitting within the section 2, and said section 2 being partially cut away internally around its upper end to 70 form a thin wall 5 surrounding the section 1. This construction provides shoulders or ledges 4^a and 5^a on the sections 1 and 2, respectively, for limiting the downward movement of the section 1 within the section 75 2.

Metal straps 6 are attached as at 7 to the inner surface of the section 2, which is hollow as clearly illustrated in the drawings. There are two of these straps 6, one being 80 arranged on each side of the limb and extending upward along the section 1, being seated in grooves 60 formed in the outer surface of said section 1. Near the lower end of each strap 6 a tongue 8 is cut therefrom 85 and bent inward as shown in Fig. 6. The reduced portion 4 of the section 1 is provided with slots 8^a to receive said tongues 8 and coiled springs 11 which have their lower ends engaged with said tongue. The upper 90 ends of said springs engage downwardly projecting tongues 10 on plates 9 secured to the outer face of the section 1 at the upper ends of the slots 8^a. These springs serve to cushion the downward movement of the section 1 within the section 2 as the weight of the body is placed upon said section 1 by the wearer in the act of walking.

The lower end portion of the section 2 is solid as at 12, except for certain passages 100 formed therein for purposes hereinafter explained. In the bottom of this solid portion 12 a substantially semispherical cavity 13 is formed and fitted with a correspondingly shaped bearing plate 14. The foot section 105 3 has a corresponding substantially semispherical cavity 15 in its upper face fitted with a similar bearing plate 16. Between said bearing plates there is fitted a ball 17 preferably provided with a central cavity 110 18 opening at the top and normally closed by a cap 24. U-shaped rods 21 and 22 have

their horizontal portions fitted in passages 19 and 20 formed diametrically through the ball 17 at right angles to each other, as shown in Figs. 1, 7 and 8. The horizontal portion of the U-shaped rod 21 may be notched, as at 23, where it straddles a horizontal portion of the U-shaped rod 22 to provide a better bearing between said rods. The legs of the U-shaped rod 21 are passed through the foot section 3 and fitted with nuts 26 arranged in cavities 27. The legs of the other U-shaped rod 22 extend upward through the solid portion 12 of the section 2 and are secured by nuts 28. The rods 21 and 22 may be passed through the passages 19 and 20 in the ball 17 while straight, and their ends and the notched portion 23 bent into proper form afterward. This structure constitutes a universal ball and socket joint between the ankle and foot sections permitting said foot section to swing laterally as well as longitudinally on the ankle section. The lateral movement is limited by a pair of rubber stops 61, Fig. 5, while the longitudinal movement is limited by other devices which will be presently described.

The foot section is provided with a toe portion 29 pivoted thereto at 30, and in the bottom of said toe portion there is a cavity 30 of groove 31 in which one end of a cord 34 is secured by a knot 36 in the cord held by a staple 37, Fig. 1. Said cord, which is preferably made of non-stretching catgut, extends up through a passage 32 in the foot section and a communicating passage 33 in the lower end of the ankle section, the upper end of said cord being secured by a knot 35 engaging the mouth of a restricted portion of the passage 33. This non-stretching cord 34 limits the relative movements of the foot and toe portions without a relative movement between the foot and ankle sections. A spring 41 is coiled about the portion of the cord 34 which is arranged in the passage 32 in the foot section and is connected at its opposite ends to hooks 38 and 39 fastened respectively to the toe portion 29 and the ankle section for yieldingly holding the parts in the natural normal positions illustrated in Fig. 1. The hook 39 preferably has a shank extending through the solid portion 12 of the section 2 and is held by a nut 40 screwed onto the upper end of said shank and engaging the top of said solid portion 12.

The solid portion 12 of the section 2 is also provided with a passage 42 in the rear portion thereof, and in this passage is arranged a flexible means 46 having a loop at its upper end engaging the reduced central portion 45 of an I-shaped plate 43 fastened as at 44, Fig. 4, to the top of the solid portion 12 over the passage 42. The lower end of the flexible means 46 has rigidly connected thereto an externally screw threaded

cylindrical member 47, the screw threads being indicated at 48, Fig. 10. Said member 47 has longitudinal grooves 49 which are engaged by tongues 51 on a plate 50 secured to the top of the foot section and through which the member 47 is loosely passed. Below said plate 50, an adjusting cap 53 is loosely fitted in a suitable bore in the heel portion of the foot section. Said cap is internally threaded, as at 57, to engage the external threads 48 on the member 47, and has a flange 54 and wrench surface 56 located in a cavity 55 in the bottom of the foot section, whereby the length of the flexible means 46 may be adjusted to suit requirements and thereby regulate the longitudinal swing as well as the proper position of the leg and of the foot section on the ankle section. It will be observed that the tongues 51 on the plate 50 serve to prevent the flexible means 46 and member 47 from turning with the cap 53, thus insuring a longitudinal movement of said flexible means when the cap is turned. As illustrated in Fig. 1, if desired, the cavities 27 and 55 in the bottom of the foot section may be covered by a sole plate 58 of any suitable material, and the cavity or groove 31 in the bottom of the toe portion 29 similarly covered by a piece of suitable material 59, Fig. 1.

It will thus be seen, that I have provided an artificial limb, as near to the human, as has yet been devised, for I have provided a limb, that will yield in any direction, and to the comfort of a wearer, and it will, also, be noted, that I have provided a limb smooth on the exterior, because of the provision I have made, to put and place all the mechanism on the inside or hollow part of the upper limb, which, also, enables me to make a limb much lighter and neater in appearance, and each limb, because thereof is adapted to any length stump.

Having thus described my invention, what I claim as new and desire to secure by Letters Patent of the United States is:—

1. In an artificial limb, the combination with two sections telescopically arranged with the end of one within the end of the other, of straps of metal arranged in grooves in the outer face of the upper member and secured to the lower section, upwardly extending tongues on the straps, plates fastened to the upper section and having downwardly extending tongues arranged in line with the tongues on the straps, coiled cushioning springs engaging said upwardly and downwardly extending tongues, and means to limit the movement of one section within the other.

2. In an artificial limb, the combination with a lower section, of an upper section having its lower end telescopically fitted in the upper end of the lower section and pro-

- vided with vertical slots therein, metal straps loosely fitted in grooves in the outer face of the upper member and secured at their lower ends to the lower member, a tongue integral 5 with each of said straps and bent to lie in one of the slots in the upper section, opposed lugs secured to the upper section and arranged in line with the tongues on the straps, said lugs also lying in said slots, and 10 coiled springs engaged with said lugs and tongues for cushioning the inward movement of the upper section in the lower section.
3. In an artificial limb, the combination with an ankle section, of a foot section, each 15 having opposed semi-spherical cavities therein, a ball arranged in said cavities, a U-shaped rod passed diametrically through said ball and pivotally connecting the same to the ankle section, and an inverted U-shaped rod passed diametrically through the 20 ball at right angles to the other rod and pivotally connecting said ball to the foot section, whereby the foot and ankle sections are connected together by a universal joint.
- 25 4. In an artificial joint, the combination with an ankle section, of a foot section, each having opposed semi-spherical cavities therein, a ball arranged in said cavities, a U-shaped rod passed diametrically through 30 said ball and pivotally connecting the same to the ankle section, and an inverted U-shaped rod passed diametrically through the ball at right angles to the other rod and pivotally connecting said ball to the foot 35 section, whereby the foot and ankle sections are provided with a universal connection, one of said rods being notched to pass the other rod through the center of the ball.
5. In an artificial limb, the combination 40 with an ankle section, of a foot section, each having opposed semi-spherical cavities therein, a ball arranged in said cavities, a U-shaped rod passed diametrically through said ball and pivotally connecting the same 45 to the ankle section, and an inverted U-shaped rod passed through the center of the ball at right angles to the other rod and pivotally connecting said ball to the foot section, whereby the foot and ankle sections are 50 provided with a universal connection, one of said rods being notched to pass the other rod at the center of the ball, and said ball
- having a cavity in the center and opening on the surface thereof for permitting the formation of said notch after the rod is passed 55 through the ball.
6. In an artificial limb, the combination with an ankle section, of a foot section pivoted thereto, a toe portion pivoted to the foot section, resilient means for holding the foot section with its toe portion in normal position with relation to the ankle section, and non-stretching means of connection between the toe portion and the ankle section for limiting the movement of the toe portion on 60 the foot section without relative movement between the foot and ankle sections.
7. In an artificial limb, the combination with an ankle section, of a foot section pivoted thereto, a toe portion pivoted to the foot 70 section, a coiled spring connected at opposite ends to the ankle section and to the toe portion, and a non-stretching cord connected at opposite ends to the ankle section and to the toe portion and passed through the coiled 75 spring, for the purpose specified.
8. In an artificial limb, the combination with an ankle section, of a foot section pivoted thereto, a flexible connection secured to the ankle section, a screw-threaded member 80 attached to said flexible connection and having a longitudinal groove therein, a cap carried by the foot portion and threaded to engage the threaded member for varying the length of said member for the purpose specified, and a plate fitted loosely around the threaded member secured to the foot section, said plate having a tongue engaging the groove in said member to prevent rotation 85 of the latter.
9. In an artificial limb, the combination with an ankle section, of a foot section pivoted thereto, an I-shaped plate secured to the ankle section, a flexible connection having a 90 loop at its upper end engaging the reduced central portion of said I-shaped plate, a screw-threaded member attached to said flexible connection and a cap carried by the foot portion and threaded to engage the threaded member for varying the length of 95 said rod for the purpose specified.

In testimony whereof I have signed my name to this specification.

MITA MICHAJLOV.
